UNITED STATES PATENT OFFICE.

THOMAS J. NEACY, OF MILWAUKEE, WISCONSIN.

SET-WORKS FOR SAW-MILLS.

SPECIFICATION forming part of Letters Patent No. 333,244, dated December 29, 1885.

Application filed October 4, 1884. Serial No. 144,704. (No model.)

To all whom it may concern:

Be it known that I, THOMAS J. NEACY, of the city of Milwaukee, in the county of Milwaukee and State of Wisconsin, have invented certain new and useful Improvements in Set-Works for Saw-Mills; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The object of my invention is an easy, accurate, and effectual means of advancing the log or timber at regular intervals for sawing the same into lumber of uniform thickness, and means for adjusting the thickness of the lumber as desired.

It consists, essentially, of a pair of ratchet-wheels keyed upon the set-shaft, a pair of pawl-bearing segmental gears pivoted upon said set-shaft and swinging around said ratchet-wheels, so that their pawls are brought into engagement therewith, a bevel-gear meshing upon its opposite sides with said segmental gears, a lever pivoted to said set-shaft and swinging about the face of a graduated quadrant and provided with a stop-block, whereby the throw of the segmental gears and the set-shaft operated thereby is controlled, and a lever for operating the bevel-gear meshing with said segmental gears.

In the accompanying drawings, like letters refer to the same parts in the several figures.

Figure 1 is an end elevation of the machine. Fig. 2 is a front elevation. Fig. 3 is a vertical section passing through the axis of the set-shaft. Figs. 4, 5, 6, and 7 are detail views of various parts of the machine detached.

A represents a quadrant-shaped cast-iron frame, secured by its broad base a' to the timbers of the carriage M. It is provided near its base with bearings for the set-shaft C and the short transverse shaft P of the bevel-gear N.

D D are segmental casings, placed over the ratchet-wheels B B, and provided on each side thereof with the hubs c c, through which the set-shaft C passes. They are provided also on their inner opposite faces with the segmental bevel-gears O O, with which the small bevel-

gear N meshes, and with the pawls d d, pivoted therein in pairs upon the pins e e, passing through said casings from side to side. These pawls d d are held in engagement with the ratchet-wheels B B by the springs d' d', secured by their shanks in said casings D. The ratchet-wheels B B are fixed within the casings D upon shaft C by the keys c' c', while the hubs c c of said casings are permitted to turn freely thereon. Between the frame A and the left-hand ratchet-wheel B, as shown in Fig. 3, the arm K is mounted by means of the broad sleeve at its lower end upon the hub of said ratchet-wheel B, the inner hub of its casing D, and a corresponding hub formed upon the frame A about set-shaft C, whereby it is adapted to turn freely about the center of said set-shaft and of the graduated quadrant scale-rack a.

The several parts just described interlock and are combined and arranged in the manner and order shown in Fig. 3.

The collars f f, recessed to receive the heads of the keys c' c', bear against the outer hubs, c c, of casings D, and retain them with ratchet-wheels B B and the swinging arm K in their proper positions. The collars f f are set as desired upon the shaft C by set-bolts f' f'. The arm K is formed in its face toward the frame A, with a long recess or channel, in which is pivoted the lever I, so as to swing outward away from the rack a on the frame A. A spring, J, attached at its lower end to the arm K, bears at its upper end against the lever I and holds the detent n', with which said lever is furnished, in engagement with the rack a.

To prevent the overthrow of the ratchet-wheels B B and set-shaft C by the inertia given thereto in operating the machine rapidly, I provide an elastic stop or brake on the arm K, against which a block or lug, h, attached to the casing D on the adjacent side of the frame A, strikes at the end of the upward throw of the actuating-lever H, keyed to the front end of shaft P. It is composed of a small hammer-shaped arm, b, pivoted at its lower end in a socket formed in the arm K, and of a spring, b', attached to the rear of said arm K, and bearing at its upper end against a rearward projection from the upper end of

the stop *b*. In its forward position, as shown in Fig. 1, where it is held by the spring *b'*, the stop *b* just clears the inner face of the rim of the ratchet-wheel *B*. When thrown back by 5 the lug *h* on the casing *D*, it binds against said rim and prevents the further advance of said ratchet-wheel and the set-shaft *C*, to which it is keyed. When at rest, the right-hand casing, *D*, as seen in Fig. 2, bears upon o the bolt-head or lug *i*, raised on bed-plate *a'*, as shown in Fig. 1.

To take up any lost motion or wear in the gears *N* and *O O*, I provide the gear *N* with two plates, *p p'*, each cog-toothed for about half its circumference to correspond exactly with the teeth *o o* of said gear *N*, Figs. 4 and 5. The smaller end or face of said gear *N* is turned down or recessed to receive the supplemental cog-toothed plates *p p'*, which nest together o and are held in place by the nut and washer *t*. A curved spring, *r*, with outwardly-projecting spurs at its approaching ends, is inserted between the gear *N* and the plates *p p'*, so that its spurs bear against said plates in 5 opposite directions and cause the teeth *o o* to overlap the teeth *o o* of gear *N*, as shown in the right-hand half of Fig. 4. It is obvious that any space left between the cogs *o o* and the cogs of the gears *O O* will in effect be taken o up by the former actuated by the spring *r*.

In the machine herein shown and described each notch of the graduated rack *a* represents one-fourth of an inch in the lateral movement of the standards or log—that is, when the detent *n'* of lever *I* rests in the first or lowest notch an upward and downward throw of the lever *H* will advance the standards one-fourth of an inch. In like manner, when the lever *I* is set at the second notch of the graduated o rack, a double throw of the lever *H* will advance the standards half an inch, and so on.

By means of the "ladder" *L*, composed of five descending steps and secured to the lever *I*, upon which it slides up and down by the band *l*, the one-fourth inch represented by each notch of the graduated rack *a* may be divided into four parts or sixteenths of an inch. The detent *n'* is formed upon the rectangular collar *n*, which surrounds said lever *I* and ladder *L*, as shown in Fig. 6. The collar *n* is provided at the front with a handle, *m*, and is supported by the spring *k*, attached at the top to its rear face and at its lower end to the arm *K*, said spring *k* holding said ladder *L* 5 snugly against the rear face of the lever *I*. When the collar *n* rests at the rear upon the middle step of ladder *L*, the travel of the standards will be indicated directly by the graduated face of rack *a*. Lowering said ladder one or two steps from the above zero-point reduces the travel of the standards by one-sixteenth and one-eighth of an inch, respectively, and vice versa. Thus the thickness of the lumber may be varied by sixteenths of an 5 inch.

The four pawls *d d* pivoted in pairs in each casing *D*, are made of slightly different lengths

to insure the engagement of one, at least, with the ratchet-wheels *B B*. To withdraw the standards to their starting-point, said pawls 7c must be disengaged from the ratchet-wheels *B B* and the set-shaft turned to the left, (viewing the machine in the position shown in Fig. 1.)

To lift the pawls, I provide the following 75 means: Two thin plates, *E*, curved to correspond with the circumference of ratchet-wheels *B B*, are pivoted to the ends of the bed *a'* of frame *A*, and inserted between the outer faces or sides of said ratchet-wheels and their 80 casings *D D*, Figs. 1, 2, and 3. Their upper rear ends are curved upward and connected by a rod, *F*, which rests upon the rear end of a lever, *G*, fulcrumed in the frame *A* and projecting at the front of the machine, as seen in 85 Fig. 1. When the lever *G* is depressed and the plates *E E* thereby raised, their thin edges engage with the points of the outer pawls *d d* of each pair and raise them out of contact with the ratchet-wheels *B B*. The said outer pawls, 90 *d d*, being the shorter of the pairs to which they belong, are provided on their undersides with the small right-angled arms *s s*, which project underneath the inner pawls *d d* of each pair, and lift them also whenever the 95 outer ones are raised.

My improved set-works operate as follows: The log having been placed upon the head-blocks in the usual manner and dogged to the standards, the stop *b* is properly set by means 100 of lever *I* and scale-rack *a*, and accurately adjusted by means of the ladder *L*, for splitting the lumber into the desired thicknesses. The log is then advanced laterally toward the saw by intervals by means of the lever *H*, the 105 upward throw of which, acting through the gear *N* and segmental gear *O*, and pawls *d d* upon the right-hand ratchet-wheel *B*, as seen in Fig. 2, advances the standards through set-shaft *C* one-half of the desired interval, while 110 the return downward throw of the lever *H*, acting through said gear *N*, the segmental gear *O*, and pawls *d d*, upon the ratchet-wheel *B* on the opposite side, advances said standards in like manner the remaining half of the 115 interval. While one casing, *D*, with its pawls *d d* is advancing, carrying with them the ratchet-wheel *B* on the same side, the opposite casing and pawls are returning to their starting-point, slipping readily over the toothed 120 face of the other ratchet-wheel *B*, which advances together with the opposite wheel *B*.

The above operation is repeated until the log or timber is completely sawed, as desired. The pawls *d d* are then lifted from the ratchet-wheels *B B* by means of lever *G*, and the set-shaft *C* turned back, and the standards thereby withdrawn to the front of the carriage.

Having thus described my invention, what I claim as new, and desire to secure by Letters 130 Patent, is—

1. In a saw-mill set-works, the combination of the set-shaft *C*, ratchet-wheels *B B*, keyed thereon, pawl-bearing bevel-gears *O O*, loosely

mounted upon said set-shaft, pawls *d d*, arranged to engage with said ratchet-wheels and alternately turn the same, bevel-pinion *N*, mounted upon transverse shaft *P*, between 5 gears *O O*, so as to mesh therewith, actuating-lever *H*, attached to shaft *P*, scale-rack *a*, lever *I K*, provided with a stop-block for limiting the throw of gears *O O*, and with a detent, *n'*, by which it may be set at any desired point on 10 said scale-rack *a*, substantially as and for the purposes set forth.

2. In a saw-mill set-works, the combination of the set-shaft *C*, ratchet-wheels *B B*, keyed thereon, pawl-bearing casing *D D*, provided 15 with gears *O O*, turning about said ratchet-wheels upon said set-shaft, bevel-gear *N*, meshing with gears *O O* and mounted upon shaft *P*, actuating-lever *H*, keyed upon shaft *P*, together with an adjustable stop for limiting the 20 movement of said gears *O O*, substantially as and for the purposes set forth.

3. The combination, in a saw-mill set-works, of the set-shaft *C*, the ratchet-wheels *B B*, keyed thereon, pawl-bearing gears *D O*, bevel-gear *N*, meshing therewith, lever *I*, provided 25 with spring-catch *n'*, graduated scale-rack *a*, and the stop-block *b*, connected with lever *I*, substantially as and for the purposes set forth.

4. In a saw-mill set-works, the combination 30 of the set-shaft *C*, ratchet-wheels *B B*, keyed thereon, pawl-bearing casings and gears *D O*, pawls *d d*, gear *N*, meshing with gears *O*, pivoted arm *K*, provided with an elastic stop, *b*, lever *I*, pivoted in arm *K* and provided 35 with detent *n'*, and scale-rack *a*, substantially as and for the purposes set forth.

5. The combination, in a saw-mill set-works, of the set-shaft *C*, ratchet-wheels *B B*, made fast thereon, pawl-bearing gears *O O*, loosely 40 mounted upon said set-shaft, pawls *d d*, gear *N*, meshing with gears *O O*, scale-rack *a*, and lever *I K*, provided with a stop to limit the movement of said gears *O O*, and with a detent, *n'*, and a ladder, *L*, having a series of 45 steps, whereby said detent *n'* is adjusted forward or backward, substantially as and for the purposes set forth.

6. In a saw-mill set-works, the combination, with set-shaft *C*, ratchet-wheels *B*, and pawls 50 *d d*, of the curved plates *E E*, rods *F*, connecting their inner ends, and levers *G*, substantially as and for the purposes set forth.

7. In a saw-mill set-works, the combination of the set-shaft *C*, ratchet-wheels *B*, pawl-bearing gears *O*, pinion *N*, meshing therewith, lever *I K*, arranged to turn about said set-shaft as a center and provided with a friction clutch or stop, *b*, and a stop-block or lug, *h*, applied to or connected with the adjacent gear *O*, and arranged to strike against said 60 clutch *b* and cause the same to engage with and arrest the movement of the adjacent ratchet-wheel *B* at any desired point, substantially as and for the purposes set forth. 55

8. In a saw-mill set-works, the combination 65 of the set-shaft *C*, a ratchet-wheel, *B*, frame *A*, provided with rack *a*, arm *K*, lever *I*, pivoted therein, spring *J*, attached to arm *K* and bearing at its upper end against lever *I*, ladder *L*, connected with the lever *I* by band 70 *l*, collar *n*, provided with detent *n'*, and spring *k*, substantially as and for the purposes set forth.

9. In a saw-mill set-works, the combination 75 of the set-shaft *C*, ratchet-wheels *B*, keyed thereon, pawls *d d*, arranged to engage with said ratchet-wheels and pivoted in or to supports which are mounted and turn upon said set-shaft about said ratchet-wheels, segmental rack *a*, and lever *I K*, arranged to swing from 80 said set-shaft as a center about said rack *a*, and provided with a detent, *n'*, adjustable in the direction of the movement of said lever, so as to divide the throw thereof between the notches in said scale *a* into smaller intervals, 85 substantially as and for the purposes set forth.

10. The combination, in a saw-mill set-works, of the set-shaft *C*, bevel-gears *O O*, mounted thereon, bevel-pinion *N*, meshing therewith and having cogs *o o*, plates *p p'*, having corresponding cogs *o' o'*, and spring *r*, arranged to force said plates *p p'* in opposite directions so as to take up the wear or lost motion between said pinion *N* and gears *O O*, with which it meshes, substantially as and for the purposes 90 set forth. 95

In testimony that I claim the foregoing as my own I affix my signature in presence of two witnesses.

THOMAS J. NEACY.
